UNITED STATES PATENT OFFICE.

ELI CALDWELL, OF EAST LAS VEGAS, TERRITORY OF NEW MEXICO.

TOOL-BOX.

SPECIFICATION forming part of Letters Patent No. 398,700, dated February 26, 1889.

Application filed December 20, 1888. Serial No. 294,216. (No model.)

To all whom it may concern:

Be it known that I, ELI CALDWELL, a citizen of the United States of America, residing at East Las Vegas, in the county of San Miguel and Territory of New Mexico, have invented 5 certain new and useful Improvements in Combination Tool-Boxes; and I do hereby declare the following to be a full, clear, and exact description of the invention, such as will 10 enable others skilled in the art to which it appertains to make and use the same, reference being had to the accompanying drawings, and to letters or figures of reference marked thereon, which form a part of this specification. 15

My invention relates to new and useful improvements in combination tool and oil boxes adapted to be situated on the right and left sides of engine-tenders, on the right and left 20 side of the coal-pit; and it consists in the novel construction and arrangement or combination of the parts thereof, as will be more fully hereinafter described and claimed.

In boxes of this class heretofore constructed 25 and employed the chief disadvantage encountered was the collection of dust, cinder, and small pieces of coal therein. Consequently the parts of the oil-cups became clogged and injured, necessitating the obtaining of others, which in time proves expensive; also, the oil-containing cans were punctured and the oil allowed to escape and be lost and to render the interior of the box filthy, and the tools and stored waste became sandy and 30 gritty, requiring cleansing before they could be used. All such inconveniences have produced a loss of time and labor, and the use of the several appurtenances constantly incurred great risk of injury to the machinery.

The object of my invention is to provide a combination-box of the character set forth which shall be dust and cinderproof, of practicable utility and strength, convenient in form and arrangement, strong and durable, readily 40 applicable without special construction, and inexpensive in manufacture. I attain this object by the construction and arrangement of box shown in the accompanying drawings, wherein like letters of reference indicate 45 similar parts in the several views, and in which—

Figure 1 is a perspective view of my im-

proved box, showing the end door thereof open, the till partially drawn out, and the small lower door raised. Fig. 2 is a longitudinal vertical section of the same. Fig. 3 is a detail perspective view of the till removed from the box. Fig. 4 is a detail section showing the arrangement of the guide-strips for the till. 55

A indicates the outer box, preferably constructed of wood, though other materials may be used, and having a door, B, hinged at one end and opening sidewise. This door B may be secured in a closed position by a suitable 60 hasp and staple. The top of the box has a metallic plate, C, formed with struck-up sides secured thereto, for a purpose which will be hereinafter set forth. The interior opposing surfaces of the box have upper and lower 65 guide-strips, a and a', secured thereto, between which projections on till D are adapted to slide and by which said till is supported above the bottom of the box. 70

The tray D is provided at front with an open-topped box or receptacle, E, consisting of the end pieces or uprights, d, and front and rear sides, d² and d³, and within the upper rear corner of this box E are secured strips e and e', which, in connection with the ends and rear side of box E, form a smaller open-topped box, E', as fully shown. The said uprights d extend only a short distance rearward from the front end of the tray or till, and between the rear ends thereof and the rear end of the tray or till a space is formed for the reception of various articles or devices used in connection with a locomotive-engine. The rear end of said till is provided with a cross-strip, d', which prevents the articles which may be held between the rear ends of the uprights d and said strip d' falling off when the till is withdrawn from the box A. 75

The lower part of the end of the box A, having the hinged door B, is provided with a small hinged door, F, which is attached to a cross-strip, F', arranged between the bottom of the till and said lower door. This door F extends across the entire width of the box A and opens upward, as shown in Fig. 1. The 80 said door F communicates with a lower elongated compartment formed between the bottom of the till D and the bottom of the box A. 85

In order that the door F may be locked

closed, vertical apertures are formed in the strip F' and the said door F, and a metallic pin, G, is inserted therein.

The receptacle E is adapted to receive the general tools—wrenches, cold-chisels, and hammers; the receptacle E' for extra oil-cups, water-glasses, and such other articles. The receptacle formed between the rear of the uprights d and the rear strip, d', is for oil cups and cans, measures, and torches, and the lower compartment entered by the lower small door is adapted to receive buggy-bars and long wrenches, as well as axes, picks, and other tools used in case of accident.

15 The metallic plate C on the top of box A is adapted to rest a rake or other hot implement thereon, and thereby save the box from being charred.

20 The many uses to which my improved device can be readily adapted are self-evident, and I do not limit myself to any special use.

The doors and hinges in my improvement are in positions where they are not easily broken or detached.

25 Having thus described my invention, what I claim as new, and desire to secure by Letters Patent, is—

1. A combination tool-box for the purpose set forth, comprising a box proper having a hinged door at one end opening sidewise, a 30 till with tool-receptacles, and a lower transversely-arranged hinged door opening upward and communicating with a lower compartment, substantially as described.

2. A combination tool-box for the purpose 35 set forth, comprising a box proper having a metallic rest-plate on the top thereof, and hinged doors at one end opening sidewise and upwardly, with devices for locking the same closed, and a till adapted to be withdrawn 40 from and projected into said box, having tool-receptacles formed at one end, and an open space or receptacle formed between the rear of said tool-receptacles and the rear end of the said till, substantially as described. 45

In testimony whereof I affix my signature in presence of two witnesses.

ELI CALDWELL.
